(57) **CLAIM**

The ornamental design for a connector cable for multiple ports, as shown and described.

DESCRIPTION

FIG. 1 is a perspective view of our connector cable for multiple ports;

FIG. 2 is a top plan view thereof;

FIG. 3 is a bottom view thereof;

FIG. 4 is a right side view thereof;

FIG. 5 is a left side view thereof;

FIG. 6 is a front view thereof; and,

FIG. 7 is a back view thereof.

The broken line showing of five different plugs in the figures is for illustrative purposes only and forms no part of the claimed design.
